CAR DOOR OPENING DEVICE
Ray D. Noorlun, 865 Deaton Ave.,
St. Paul, Minn. 55102
Filed Mar. 8, 1966, Ser. No. 541,424
12 Claims. (Cl. 81—3)

This invention relates to an improvement in a car door opening device and deals particularly with a tool useful in opening a locked automobile door from the outside of a car.

Many automobiles which are produced at the present time are equipped with car door locks which are actuated by a reciprocable locking button extending through the frame of the door window. When it is desired to lock the car from the outside, the locking button is pushed down while the operating handle is held in a predetermined position. When the door is closed the door is automatically locked and can only be opened by the use of a key. Very occasionally, the car operators forget to remove the keys from the ignition switch prior to closing the door and thus are locked out with no simple means of gaining access to the interior of the car. Tools have been provided which are designed for insertion between one of the windows and its frame to lift the locking button and to unlock the door. However, no such tool with which I am familiar operates effectively.

It is an object of the present invention to provide a tool which may be readily inserted between a window and its frame, the window usually comprising the ventilating window in the forward part of the front window. The tool is provided with a notched end designed to straddle the shank of the locking button. A flat spring which is normally biased toward diverging relation from the notched end of the tool is also provided at its extremity with a notch designed to straddle the shank of the locking button. Means is provided for holding the flat spring in surface contact with the notched end of the tool until the locking button is engaged in the notch. As the aligned notches in the spring and tool end straddle the locking button, the spring is automatically disengaged and allowed to spring away from the notched end of the tool thus engaging the locking button and raising it into unlocked position.

A feature of the present invention resides in the fact that the tool may be formed of an elongated strip of flat metal and the spring may comprise a thin flat strip which does not greatly increase the thickness of the tool when held in surface contact therewith. As a result, the notched end of the tool may be readily inserted between the ventilating window and its frame by flexing the resilient gasket which normally forms a seal between this window and its frame. The tool may be shaped to angle back toward the front window of the vehicle which is rearwardly of the ventilating window. Thus, the notched end of the tool may be slid along the window frame of the front window until the notched end engages the shank of the locking button. Engagement of the locking button in the notch acts to release the spring from engagement with the notch and to permit the spring to move toward its normal diverging relation to the notched end of the tool. This action causes the notch of the spring to engage beneath the enlarged upper end of the locking button and to raise the locking button into unlocked position.

A further feature of the present invention resides in

2

the fact that in preferred form the tool includes a pair of elongated thin metal strips which are pivotally connected together so that the notched end of the blade may be angularly related to the handle end thereof.

5 As the tool is inserted between the ventilating window and its frame, the two parts of the tool body may be pivoted into the desired angular relation so that the notched end of the tool may engage the locking button.

A further feature of the present invention resides in 10 the fact that the normally diverging spring is pivotally connected to the notched end of the tool at a point spaced from this end. A finger on one of these parts extends through the notch in the upper part and holds the two parts in substantial surface contact with the notches out of complete registry. The notches are so

15 shaped that as they are moved into locking button encircling position, the spring is pivoted to some extent relative to the notched end of the tool thus disengaging the locking ear and permitting the separation of the notched end of the tool and the notched end of the spring.

While the tool has been described as being insertable 20 between the ventilating window and its frame, the tool is also of sufficient length to extend through any vehicle window on one side of the car and to engage the locking button on the opposite side thereof. Thus, if any of the windows are slightly open, the tool may be inserted 25 through this limited space and may function to unlock the door on the opposite side of the car.

30 These and other objects and novel features of the present invention will be more clearly and fully set forth in the following specification and claims.

In the drawings forming a part of the specification:

FIGURE 1 is an elevational view showing the tool 35 in position about the locking button of a car door just after the locking button has been elevated into unlocked position.

FIGURE 2 is a sectional view through a portion of a 40 car door equipped with a ventilating window and a regular vertically movable window and showing the manner in which the tool may be inserted between the ventilator window and its frame to engage the locking button normally positioned at the opposite side of the door.

FIGURE 3 is a perspective view of the end of the 45 tool showing the general construction of the handle blade and spring when the spring is in diverging position.

FIGURE 4 is a top plan view of the notched ends 50 of the spring and of the handle blade when these two elements are in interlocked position.

FIGURE 5 is a sectional view through a portion of 55 the handle blade and spring, the position of the section being indicated by the line 5—5 of FIGURE 4.

FIGURE 6 is a bottom plan view of the handle blade and spring in interlocked position.

FIGURE 7 is a bottom plan view of a modified form 60 of construction in readiness for operation.

FIGURE 8 is a perspective view of the structure shown 65 in FIGURE 7 in open position.

FIGURE 9 is a bottom plan view of an end of the 70 elongated support or blade.

FIGURE 10 is a cross sectional view through the blade 75 on the line 10—10 of FIGURE 9.

FIGURE 11 is a bottom plan view of the springs.

FIGURE 12 is a sectional view through the spring 80 on line 12—12 of FIGURE 11.

FIGURE 13 is a sectional view through the combined

blade and spring, the position of the section being indicated by the line 13—13 of FIGURE 7.

As will be obvious, the door unlocking tool A may vary considerably in its specific shape or design. In the particular form illustrated, the device A includes an elongated strip 10 of metal or other fairly rigid material which is pivotally connected at 11 to a forward handle blade portion 12. The pivot 11 preferably holds the handle parts 10 and 12 under friction so that relative rotation between the parts is resisted by friction. This arrangement is provided so that the two parts of the handle will tend to remain in an adjusted angular relation.

As is indicated in the drawings, the forward blade portion 12 is provided in its end with a notch indicated in general by the numeral 13. The notch 13 is shown as having tapered inlet portions 14 and 15 tending to guide the shank of the locking button toward the center of the notch. The notch 13 is also provided with a narrower portion having generally parallel sides 16 and 17 communicating with the tapered portions 14 and 15 leading to the notch end 19.

A flat spring 20 is pivotally connected at 21 to the handle portion 12 and is substantially coextensive therewith. A notch 22 is provided in the end of the spring 20 which more or less registers with the notch 13 and the spring 20 is normally bent so as to diverge away from the plane of the handle portion 12. The notch 22 is shown as having generally parallel sides 23 and 24. A narrower notch extension 25 is provided at the base of the notch 22 and an integral finger 26 projects laterally of the notch extension 25. The finger 26 is offset from the plane of the notched end of the spring 20, the amount of offset being equal to or slightly greater than the thickness of the material forming the handle portion 12. This offset finger 26 is designed to extend beneath the edge 17 of the narrower portion of the notch 13 when the spring strip 20 is substantially aligned with the end of the handle blade 12. When in this position, the two notches are not in complete registry.

In actual practice the undersurface of the end of the blade 12 is notched or grooved as indicated at 27 to reduce the thickness thereof. This groove 27 is best illustrated in FIGURES 5 and 6 of the drawings. The flat spring 20 is usually relatively thin as compared to the thickness of the blade 12 and the groove 27 is of proper depth so that the hook end 26 or offset ear does not extend below the lower surface of the member 12.

As is indicated in the drawings, the tapered edge 14 of the notch 13 of the blade 12 extends inwardly beyond the inner edge 29 of the side 23 of the notch 22 in the spring 20. Furthermore, the inlet edge 15 of the notch 13 is positioned outwardly of the inner edge 30 of the notch side 24 when the ear 26 is engaged beneath the edge 17. Thus, as the tool is urged toward the shank, the tapered edge 15 urges the shank of the locking button against the edge 30 of the spring notch 22 thus acting to pivot the spring about the axis of the pivot 21 as the shank of the locking button moves toward the base of the notch. This pivotal movement of the spring 20 continues until the ear 26 is disengaged from beneath the edge 17. As soon as the ear 26 is disengaged, the spring 20 springs into diverging relation to the blade 12 moving the locking button into unlocked position.

FIGURE 1 of the drawings illustrates the locking button 31 projecting from the window frame 32. The button 31 is provided with an enlarged head 33 which may be engaged by the sides of the notch to move the locking button upwardly. It should also be noted that the tool will work equally well in inverted position. When used in the manner illustrated in FIGURES 1 and 2 of the drawings, the notch 22 of the spring 20 engages the locking button 31 to move the same upwardly into the position shown in FIGURE 1. If the tool is held in inverted position, the enlarged upper end 32 of the locking button is engaged by the notch 13 in the blade 12 and the spring

20 engages against the upper surface of the window frame 32 to force the blade upwardly to unlock the button.

FIGURE 2 diagrammatically illustrates the manner in which the tool is used. In usual practice, the thin bladed tool is inserted beneath the ventilating window 35 of the car B, the resilient gasket forming a seal at this point being flexed out of the way to permit admission of the tool. The two parts 10 and 12 of the tool are usually bent into angular relation as illustrated in FIGURE 2 and the tool is fed into the car while in such an angular position. By manipulating the end 36 of the handle 10 which remains on the exterior of the car, the notched end of the tool may be slid and swung into position embracing the shank 31 of the locking button. The tapered edge 15 of the slot 13 acts as a cam to force the shank of the locking button against the side 24 of the spring 20 thus pivoting the spring 20 an amount necessary to disengage the ear 26 from the side 17 of the notch 13. The spring then swings away from the blade 20 to move the locking button into unlocked position in the manner described. The position of the shank 31 of the locking button as it enters the notches is indicated in dotted outline in FIGURE 4 of the drawings. It will be noted that the shank 31 is of a diameter approximately equal to the width of the base portion of the notch 17 and the cam surface 15 is of sufficient length to cause disengagement of the ear 26.

The particular arrangement illustrated is advantageous as the ear 26 is maintained within the confines of the blade 12 and the ear 26 is centrally located relative to the spring so as to hold the spring in surface contact with the blade 12 without danger of striking a part of the automobile body during insertion and becoming accidentally disengaged. However, the ear 26 could be located either on a side of the spring 20 or on the opposite side of the blade 12 if preferred. It should also be noted that in the event the tool is always to be used with the spring 20 uppermost, the side 14 of the notch 13 could be eliminated although in practice the notch side 14 acts to assist in protecting the spring from accidental movement.

In FIGURES 7 through 13 of the drawings a modified form of construction is illustrated, being shown in general by the letter C. The main point of difference between the tool A and the tool C lies in the fact that in the tool A different dies are required for forming the ends of the blade and spring, while in the tool C, the same die may be used to form the ends of both of these members.

In general, the tool C includes an elongated blade 40 similar to the blade 12 of the tool A. The blade 40 may be pivotally connected to a handle portion 10 by a pivot 11 similar to the construction which has been previously described.

The blade 40 is provided with a notch 41 in its end 55 extremity, the notch 41 including a pair of generally parallel sides 42 and 43 which are at an angle relative to the longitudinal axis of the blade. The edge 42 is designed to form a cam surface designed to bear against the shank 31 of the push button beneath the head 33. An aperture 44 having a countersunk area 45 encircling the same is provided in the blade 40 spaced rearwardly from the notch 41.

The spring 46 is pivotally connected to the blade 40 by means of a pivot 47 which is sufficiently tight to 65 resist relative pivotal action between the spring and the blade. The spring 46 is provided with a notch 47 in its end extremity, the notch 47 being identical in shape to the notch 41 and including generally parallel sides 49 and 50 connected by a rounded end 51. The side 49 is 70 inclined in the manner to act as a cam surface as the tool is engaged about the shank 31 of the locking button.

An attaching button 52 is supported upon the spring 46 in the manner best illustrated in FIGURE 12 of the drawings. The button 52 includes a shank 53 having a 75 reduced diameter portion 54 which extends through an

aperture 55 in the spring. The end of the reduced diameter portion 54 is riveted over as indicated at 56 to anchor the button to the spring. The button includes an enlarged head 57 which is of proper diameter to extend through the aperture 44 in the blade 40.

As is indicated in the drawings, the notch 47 of the spring 46 is reversed relative to the notch 41 of the blade 40. As a result, when the spring and blade are in surface contact, the cam edges 42 and 49 are in opposed relation and form a generally V-shaped notch. When in the position illustrated in FIGURE 7, the head of 57 of the button 52 is locked over the countersunk portion 45 surrounding the aperture 44 and the head of the button holds the spring in substantial surface contact to the blade 40. However, as the shank of the operating button 31 is engaged in the V-shaped notch formed by the cam surfaces 42 and 49, these cam surfaces are urged apart, pivoting the spring 46 about the axis of the rivet 47 until the head 57 of the button 52 is disengaged from the countersunk area 45 surrounding the aperture 44 and the head 57 becomes aligned with the aperture. At this point, the force of the spring will pull the button head through the aperture and the spring 46 will flex away from the blade 40 into the open position illustrated in FIGURE 8.

In illustrating the tool C, the spring has been indicated as secured to the undersurface of the blade. As in the previous construction, the tool is invertable and will operate either with the blade uppermost or with the spring uppermost. Most commonly, the tool is used with the spring 46 above the blade so that the spring will engage beneath the head 33 of the locking button 31 and move it vertically into unlocked position.

In accordance with the patent statutes, I have described the principles of construction and operation of my improvement in a car door opening device, and while I have endeavored to set forth the best embodiment thereof, I desire to have it understood that changes may be made within the scope of the following claims without departing from the spirit of my invention.

I claim:

1. A door opening device for use in combination with car doors having a reciprocable locking button projecting from the door, the device comprising an elongated strip of relatively rigid material, said strip having a notched end for receiving said button, a spring pivotally connected to said blade at a point spaced from said notched end, said spring having an end normally diverging away from said notched end, said spring end having a notch therein designed to receive the locking button, means cooperable between said elongated strip and said spring for holding said spring in surface contact with said strip in one position of said spring, and a cam surface on one of said notched ends engageable against said locking button as said locking button is received into the notch of said strip to disengage said last named means, whereby said notched end of said spring will flex away from said notched end of said strip.

2. A tool for use in opening locked vehicle doors having a reciprocable locking button projecting from the door, the locking button having an enlarged end, and having a shank adjoining said enlarged end, the tool including an elongated handle member having a notched end, a spring member pivotally connected to said handle member at a point spaced from said notched end, said spring member being substantially coextensive with said handle member, and said spring member normally being supported in diverging relation from said handle member, said spring member having a notched end designed to receive the shank of the locking button, and a cam surface adjoining the notch in one of said members, a locking member on one of said members engageable with the other member in one pivoted position thereof to hold said members in substantial surface contact, the notch in one of said members being somewhat misaligned from the notch in the other member when said

locking member is holding said members in surface contact, said cam surface engaging said button shank as said shank is received into said notches thereby causing said spring member to pivot into position to disengage said locking means, whereby the notched end of the spring and the notched end of the handle member may spring apart and one of said notches may engage the enlarged end of said locking button to raise the same.

3. The structure of claim 3 and in which said handle member includes a pair of relatively pivotal elongated blades.

4. The structure of claim 3 and in which said locking member comprises an offset ear on one of said members engageable over a portion of the other member.

5. The structure of claim 3 and in which said locking member comprises an offset ear on one of said members engageable through the notch of the other member and against a portion of the surface thereof.

20 6. A door unlocking device for car doors having a reciprocable locking button projecting from a frame surface of the car, the button having a shank and an enlarged head, the device comprising an elongated handle member, a spring member supported by said handle member at a point spaced from one end thereof and normally diverging therefrom, one of said members having a notched end designed to encircle said shank but not said head, a cam surface on the other of said members in the path of movement of the shank when received by said notched end, locking means on one of said members engageable with the other member to hold said members in substantial surface contact, said locking means being disengaged by engagement of said shank against said cam surface, whereby said spring member will spring into diverging position to engage said enlarged head and slide said locking button.

25 7. A door unlocking device for car doors having a reciprocable locking button projecting from a frame surface of the car, the button having a shank and an enlarged head, the device comprising an elongated handle member, a second member supported by said first member at a point spaced from an end thereof, said second member having an end substantially coextensive with said end of said handle member, being resiliently urged said ends apart, a locking means on one member engageable with the other member to hold said ends in substantial surface contact, one of said members having a notched end designed to encircle the shank, but not the head, of said locking button between said head, and said frame surface from which said locking button projects, and means in the path of movement of said shank when entering said notched end for disengaging said locking means, whereby said members may spread into diverging relation and urge said head away from said frame surface.

30 8. The construction described in claim 8 and in which said locking means includes an offset ear on said one member extending into the notch of the other member and engaging said other member adjacent the edge of said notch.

35 9. The construction described in claim 8 and in which said locking means includes a rivet projecting from one of said members and having an enlarged head thereupon, said other member having an aperture therethrough through which said enlarged head may extend, said enlarged head being engageable over a portion of said other member adjoining the aperture.

40 10. The construction described in claim 10 and including a counter sunk area encircling said aperture and over which said rivet head engages.

45 11. The construction described in claim 10 and in which said notched ends on said strip and on said spring are of identical shape.

50 12. A door opening device for use in combination with car doors having a reciprocable locking button projecting from the door, the device comprising a pair of

longitudinal strips having adjacent free ends normally biased apart, latch means for holding said free ends together and releasable upon engagement with the reciprocal button, and means provided on one of said free ends for gripping said button and moving said button into an unlocking position upon release of said latch means.
